ALBERT H. DE VOE, OF WESTFIELD, NEW JERSEY, ASSIGNOR TO THE SINGER MANUFACTURING COMPANY, A CORPORATION OF NEW YORK.

NEEDLE-BAR MECHANISM.

1,296,633.

Specification of Letters Patent. Patented Mar. 11, 1919.

Application filed April 24, 1918. Serial No. 230,399.

To all whom it may concern:

Be it known that I, ALBERT H. DE Voe, a citizen of the United States, residing at Westfield, in the county of Union and State 5 of New Jersey, have invented certain new and useful Improvements in Needle-Bar Mechanisms, of which the following is a specification, reference being had therein to the accompanying drawings.

10 This invention relates to sewing machines and particularly to a needle-bar mechanism therefor.

There is a limit beyond which the usual cross-bar cannot be extended on either side 15 of the lower end of the needle-bar to increase the distance between parallel rows of stitches without liability of the cross-bar springing or tilting and throwing the needles sustained thereby out of coöperative relation with the 20 lower stitch-forming instrumentalities. It is an aim of the present invention to reinforce and embrace the cross-bar carried by the needle-bar to hold the needles against end-wise and lateral displacement, that is, to 25 hold the needles in their proper paths for co-operation with the lower stitch-forming instrumentalities.

The needles in the type of sewing machines to which the present invention relates 30 usually have their shanks positioned in a socket in the needle-bar and are clamped by a screw extending transverse the cross-bar. In setting a needle in position the operator in tightening up the clamp screw is liable to 35 flex and permanently bend the cross-bar because of the relatively considerable distance between the point of application of the screw driver and the needle-bar. It is an aim of the present invention to brace the 40 cross-bar between the needle-bar and its extremity in order to lessen if not eliminate the danger of flexing or bending the cross-bar when replacing a needle.

A preferred form of the invention consists 45 of a brace of plate-like form fixed to the needle-bar above and also within the head of the machine and fixed also to a cross-bar at a distance from the junction of the bars for preventing tilting of the cross-bar about the 50 junction. And it consists also in a steady or rest having surfaces located on either side of the needle-bar and in contact with the rear

of the cross-bar which is thereby prevented from angular rotation about the axis of the needle-bar as it moves laterally up and down 55 during the operation of the machine.

An embodiment of the invention is illustrated in the accompanying drawings, in which Figure 1 is a front elevation of the head and part of the overhanging arm of a 60 sewing machine. Fig. 2 is an end elevation of the same. Fig. 3 is a plan view of the invention with the lower extremity of the head of the machine appearing in section and Fig. 4 is a detail showing the connection between the needle and cross-bars. 65

On the end of the overhanging arm 1 of the frame of a machine is the usual head 2 having spaced bearings 3-3 for a needle-bar 4 which is reciprocated from a shaft 5 in 70 the overhanging arm through a crank-arm 6 connected by the link 7 to a collar 8 on the needle-bar, all of which is well known construction.

As shown in detail in Fig. 4 the lower end 75 of the needle-bar is reduced to form a shoulder 9 and stud 10 which is shorter than the aperture in a collar 11 designed to embrace the stud. A screw 12 threaded into the collar is adapted to thrust against the stud end 80 10 and because of the slot 13 therein, which communicates with the internally threaded socket 14 that receives a thread ended pin 15 extending upwardly from the cross-head 16, to thereby firmly secure the cross-head to the 85 needle-bar. The cross-head 16 is channeled to receive an edge 17 of the relatively thin cross-bar 18 and is apertured to receive the holding screws 19. Adjacent the cross-head 16 and extending substantially the length of 90 the needle-bar and in the plane defined by the intersecting needle- and cross-bars is a brace 20 of platelike form which is secured by screws 21 to the cross-bar 18. The brace 20 has a portion 22 secured by screws 23 to a 95 lateral extension of the split collar 8 and has a similar portion 23' at its upper end secured by screws 24 to a lateral extension on a split collar 25 gripped to the needle-bar above the head of the overhanging arm. 100

With the needle- and cross-bars braced as has been described, the latter bar is held positively in a definite intersecting relation with the needle-bar and the angle between

the two bars will be maintained constant. In this way the needles 26 are prevented from endwise displacement.

To confine the cross-bar 18 against angular rotation about the needle-bar as an axis and to guard against springing and possibly flexing the cross-bar 18 when the screws 27 clamping the needles in position are set home by an operator, a steady or rest 28 is secured 10 to the lower portion of the head of the machine with its flat bearing surfaces 29 arranged on opposite sides of the needle-bar intermediate the same and the ends of the cross-bar 18. The steady or rest 28 is secured by screws 30 to the angles 31 which are provided with slots 32 receiving the screws 33 which are tapped into a bracket 34 positively secured by the screw 35 to the rear face of the depending portion 36 of the head 20 of the machine. Preferably the angles 31 have their rearwardly extending legs secured in slideways 37 formed in the sides of the bracket 34. A plate 38 is secured by screws 39 to the brace 20 and in its opposite ends apertures 40 are provided to guide the thread leading from the supply and from the stationary guide 41 through the same to the needles, the plate 38 being bent as clearly shown in Fig. 3 to clear the head of the machine when the needle-bar is reciprocated.

Having thus set forth the nature of the invention, what I claim herein is—

1. In a sewing machine, a needle-bar mechanism comprising a reciprocatory needle-bar, a cross-bar secured to the lower end thereof, and means secured to the cross- and needle-bars, respectively, at points removed from their junction for bracing the cross-bar.

2. In a sewing machine, a needle-bar mechanism comprising a reciprocatory needle-bar, a cross-bar secured to the lower end thereof, and means secured to the needle-bar at a plurality of spaced points and to the cross-bar at a point removed from the junction of the bars for maintaining the needle- and cross-bars in definite angular relation.

3. In a sewing machine, a needle-bar mechanism comprising a reciprocatory needle-bar, a cross-bar secured to the lower end thereof, and bracing means secured to the needle-bar at its upper end and to the cross-bar away from the junction of the two bars for maintaining the bars in definite angular relation.

4. A sewing machine having an overhanging arm terminating in a head having spaced and aligned bearings formed therein, a needle-bar slidably mounted in said bearings, a cross-bar secured to the lower end of the needle-bar and adapted to carry needles, a brace secured to said needle-bar above and also intermediate said bearings and to said cross-bar at a distance from the junction of the two bars.

5. A sewing machine having an overhanging arm terminating in a head provided with spaced and aligned bearings, a needle-bar slidably mounted in said bearings, a cross-bar secured to the lower end 70 of the needle-bar and adapted to carry needles, collars gripped on said needle-bar above and intermediate the bearings in said head, each collar having a lateral extension, a brace secured to the lateral extensions of 75 said collars and to said cross-bar at a distance from the junction of the needle-bar and cross-bar.

6. A sewing machine having a needle-bar, a cross-bar secured substantially midway between its ends to the lower end of the needle-bar, means for securing needles to the cross-bar, and stationary means contacting directly with the cross-bar and located in rear of the cross-bar for preventing the lateral 85 displacement of the needles carried thereby.

7. A sewing machine having a needle-bar, a cross-bar secured to the lower end of the needle-bar, means for securing needles to 90 said cross-bar, and means in addition to the bars for preventing endwise and lateral displacement of the needles.

8. A sewing machine having a needle-bar, a cross-bar secured to the lower end of the 95 needle-bar and adapted to carry needles, means rigidly connecting the needle- and cross-bars at points remote from their junction for preventing endwise displacement of the needles, and means for preventing lateral 100 flexure of the cross-bar and lateral displacement of the needles.

9. A sewing machine having a needle-bar, a cross-bar adapted to carry needles secured to the needle-bar at its lower end, stationary 105 means contacting with the cross-bar to prevent lateral flexure of the cross-bar and consequent lateral displacement of the needles, and means for maintaining a constant angular relation between the needle-bar and the cross-bar whereby endwise displacement of the needles is prevented.

10. A sewing machine having a needle-bar, a cross-bar secured thereto at its lower end and adapted to carry needles, a plate secured to the needle-bar and cross-bar at points removed from their junction and located in the plane defined by said bars for holding the needles fixed against endwise displacement.

11. A sewing machine having a needle-bar, a cross-bar secured thereto at its lower end and adapted to carry needles, and guiding means on both sides of said needle-bar and contiguous to said cross-bar for preventing lateral displacement of the needles.

12. A sewing machine having a needle-bar, a cross-bar secured thereto at its lower end and adapted to carry needles, and guiding means contiguous to said cross-bar for 130

5 preventing lateral displacement of the needles, said guiding means having bearing surfaces spaced on opposite sides of and extending approximately parallel to the needle-bar.

10 13. A sewing machine having a needle-bar, a cross-bar secured thereto at its lower end and adapted to carry needles, guiding means on both sides of said needle-bar and contiguous to said cross-bar for preventing

lateral displacement of the needles, said guiding means including a plate having bearing surfaces spaced on opposite sides of and extending approximately parallel to the needle-bar, and a bracket adjustably 15 supporting said plate and supported by a fixed part of the machine.

In testimony whereof, I have signed my name to this specification.

ALBERT H. DE VOE.
